UNITED STATES PATENT OFFICE.

WILLIAM P. THOMSON, OF NEW YORK, N. Y., ASSIGNOR TO THE RAIL JOINT COMPANY,
OF NEW YORK, N. Y., A CORPORATION OF NEW YORK.

RAIL-JOINT.

1,195,872.

Specification of Letters Patent. Patented Aug. 22, 1916.

Application filed May 24, 1915. Serial No. 30,137.

To all whom it may concern:

Be it known that I, WILLIAM P. THOMSON, a citizen of the United States, residing at New York, in the county of New York and State of New York, have invented certain new and useful Improvements in Rail-Joints, of which the following is a specification.

This invention relates to a novel and useful rail joint construction having improved means for more effectively and advantageously distributing the clamping effect of the joint bolts, particularly when applied to splice bars which have a substantially greater lateral resistance in their head members than is found in said member of ordinary angle bars.

The present invention is primarily designed to augment the bolting efficiency of a rail joint at the points or zones where it has been demonstrated that the clamping of the bolts may be utilized to the best advantage, and at the same time to relieve the abutting ends of the rails of such a vise-like grip as is prevalent.

To that end, the invention has for its object to provide an economical short rail joint wherein a solid clamping effect is maintained up to the very ends of the splice bars and throughout the said zones.

It has been determined that, under such conditions of lateral stiffness in the head members of splice bars, the effective resistance of a rail joint to deflection or elevation under load conditions is essentially dependent upon the degree of firmness with which the splice bars are clamped against the rails at distances of approximately three to six inches away from each of the rail ends. These locations constitute the effective bolting areas or zones, and are usually occupied by a single joint bolt which, alone, is not adequate to hold the splice bar with sufficient firmness to accomplish the best results.

Accordingly, the present invention recognizes the desirability of increasing the bolting capacity of a rail joint within the most effective bolting areas or zones, whereby the splice bars will be held firmly in place at such points when the load is imposed thereon, and a fuller effect of the efficiency at the middle of the bars will be realized than if the bars were free to yield laterally at said effective bolting areas or zones.

Another important and practical object of

the invention, incident to increasing the bolting capacity of the joint in the most effective places, is to provide a construction possessing special utility in connection with splice bars of the heavily reinforced type, so that such bars may be made much shorter than is the common practice, and an increased carrying capacity may be obtained, in combination with a very great saving of metal.

With these and other objects in view which will be recognized by those familiar with this art, the invention consists in the novel construction, combination, and arrangement of parts hereinafter more fully described, illustrated, and claimed.

The essential feature of the invention involved in the concentration and localization of the bolting means within the most effective bolting areas or zones, is necessarily susceptible of structural modification and embodiment in various forms of construction without departing from the spirit or scope of the invention, but a preferred and practical embodiment of the invention is shown in the accompanying drawings, in which:—

Figure 1 is a side elevation of a short low-cost rail joint constructed in accordance with the present invention. Fig. 2 is a vertical cross sectional view on the line 2—2 of Fig. 1, the line of section being through one of the bolts of the bolting-couplet for one rail. Fig. 3 is a similar view on the line 3—3 of Fig. 1 through the other bolt of the same bolting-couplet. Fig. 4 is a side elevation of the joint showing one of the rails removed to better illustrate the relation between the inner main splice bar and the outer supplemental clamping bar. Fig. 5 is a detail plan view of the preferable cambered spring-type clamping bar.

Similar reference characters designate corresponding parts throughout the several figures of the drawings.

The invention fundamentally includes, in combination with the rails R, a main splice bar 1 fitting the fishing spaces of the rails, an outer supplemental clamping bar 2 binding against the outer side of the main splice bar, and a plurality of bolts. As herein indicated, the most effective bolting area is located at a substantial distance away from the ends of the rails, ordinarily approximating from three to six inches. In order to increase the bolting capacity and clamping ef-

fect of the joint within these areas, the present invention provides for locating in each of such areas a double-bolting unit consisting of a pair of joint bolts 3—3 arranged closer together than customary and disposed at such distance away from the rail end that the said units are distinctly isolated. Usually, though not necessarily, this grouping or pairing of the joint bolts into separate bolting units, one unit for each rail, involves placing the bolts in each unit closer together than the distance between the middle of the joint and the nearest one of said bolts, thus leaving a relatively extended unbolted area within the middle of the joint between the inner bolts of the opposite bolting units. This provides a structure having an augmented bolting capacity within each of said effective areas or zones that insures a solid clamping effect up to the extreme ends of the splice bars, as well as throughout such areas or zones. In this connection, it will be understood that this feature of the invention is practical and effective regardless of the length of the splice and clamping bars. However, a preferred and useful application of this improvement in the bolting means of a joint is shown in the accompanying drawings, and further reference thereto will now be made.

As shown in the drawings, the present invention involves another feature of practical importance. This is the feature of having a relatively short inner main splice bar 1 and a longer outer clamping bar 3, so that the end portions of the clamping bar project beyond the ends of the splice bar and receive therethrough the outermost bolt of the bolting units. As plainly illustrated in Figs 1, 3 and 4 of the drawings, the outermost bolt of each bolting unit passes through the rail web and the ends of the clamping bars 2 upon opposite sides of the rail, while the inner bolt 3 of the same unit passes through both bars 1 and 2 and also through the rail web, thus realizing the purposes of the invention in the most effective manner. In addition to this feature of construction, it may also be found preferable to make the clamping bar of spring steel and camber it slightly, as indicated in Fig. 5 of the drawings, so that it will have a substantial locking effect upon the nuts of the bolts when the end portions of said bar are drawn firmly into place against the ends of the splice bar by the tightening up of the bolts of the double-bolting unit.

While the invention is susceptible of general application to splice bars of different forms of construction, in so far as the features of improvement already referred to are concerned, nevertheless it is preferable to utilize the improvement in combination with heavily reinforced splice bars so that the latter may be made shorter than usual, while

at the same time an increased carrying capacity may be obtained with a saving of metal. This phase of the invention involves the employment of a splice bar having the characteristics of the bar shown in Figs 2 and 3 of the drawings. In other words, the illustrated form of splice bar 1 embodies a distribution of metal which makes the bar substantially stronger, both vertically and laterally, than the conventional angle bar. In this type of bar, the portion thereof lying above the horizontal neutral axis is materially stronger laterally than the ordinary forms of splice bars. It will be observed that the section modulus of the portion of the bar lying above the horizontal neutral axis is increased over common practice to a point where it approximately balances the section modulus of the portion of the splice bar lying below the horizontal neutral axis. Such distribution of metal, when limited to practical working conditions, requires the use of a very materially enlarged and widened head 5 including an inner head projection 6 and an outer head projection 7 providing, in combination with the web of the bar and its foot, an I-beam distribution of metal such as prevails in the rail section itself. The practical importance of this increase of lateral resistance in the head 5 of the splice bar will be appreciated when it is noted that as the inside bolts of a rail joint are moved farther away from the rail ends, and consequently away from the middle of the splice bar itself, the tendency of the bars to bulge outwardly from the rails at the center of the joint is increased. However, the additional lateral stiffness provided for in the enlarged head of a bar of the type referred to, not only off-sets this increased tendency of the bar to bulge outward at the middle, but in fact renders such tendency even less than it would be if ordinary angle bars were employed with the inside bolts closer to the rail ends than is required in accordance with the present invention. Furthermore, in the preferable construction referred to, the splice bar, having the distribution of metal described, is formed at its outer side with a channeled seat receiving the outer clamping bar 2. This channeled seat is formed with upper and lower beveled bearing faces 8 and 9 respectively, which converge inwardly toward the rail, and are clampingly engaged by correspondingly beveled bearing faces 10 formed at the inner side of the upper and lower edge portions of the clamping bar 2. By reason of this particular construction and fit of the main splice bar and the supplemental clamping bar, a particularly advantageous result is obtained, namely that of adding the vertical carrying capacity of the clamping bar to that of the splice bar.

From the foregoing, it is thought that

the essential features of the invention will be recognized without further description, and it will also be understood that various changes in the form, proportion, and minor details of construction may be resorted to without departing from the spirit of the invention or scope of the appended claims.

I claim:

1. A rail joint including, in combination, the rails, a splice bar having a reinforced head portion having a continuous bearing under the heads of both rails, and the joint bolts grouped in distinctly isolated bolting units located in areas at a distance from the rail ends, the bolts of each unit being disposed closer together than the distance between the innermost bolt of each unit and the adjacent rail end.
2. A rail joint including, in combination, the rails, a splice bar having a reinforced head portion having a continuous bearing under the heads of both rails, and the joint bolts grouped in distinctly isolated bolting units located in areas at a distance from the rail ends, the bolts of each unit being disposed closer together than the distance between the innermost bolt of each unit and the adjacent rail end thereby leaving a relatively extended unbolted area within the middle of the joint between the inner bolts of the opposite units.
3. A rail joint including the rails, a splice bar, an outer clamping bar, and the joint bolts grouped into distinctly isolated bolting units located in bolting areas at a distance from the rail ends, certain of the bolts extending through only the clamping bar and the rails.
4. A rail joint including the rails, a splice bar, an outer clamping bar, and the joint bolts grouped into distinctly isolated bolting units located in bolting areas at a distance from the rail ends.
5. A rail joint including the rails, a splice bar, an outer clamping bar, and the joint bolts grouped into separate bolting units located in bolting areas at a distance from the rail ends leaving a relatively extended unbolted area within the middle portion of the joint.
6. A rail joint including the rails, a splice bar, an outer clamping bar, and the joint bolts grouped into separate bolting units located in bolting areas at a distance from the rail ends, the bolts of each unit being arranged closer together than the distance between the innermost bolts of the opposite units.
7. A rail joint including the rails, a splice bar, an outer clamping bar, and the joint bolts grouped into separate bolting units located in bolting areas at a distance from the rail ends, the bolts of each unit being arranged at least as close together as the distance between the innermost bolt of each unit and the adjacent rail end.
8. A rail joint including the rails, an inner splice bar, an outer clamping bar engaging the outer side of the splice bar, and a closely disposed double-bolting unit engaging the bars at a distance from the rail ends.
9. A rail joint including the rails, an inner splice bar, a coacting outer clamping bar, and a double bolting-unit consisting of a pair of relatively close bolts engaging both bars at a distance from the rail ends.
10. A rail joint including the rails, a splice bar, a clamping bar, and joint bolts, certain bolts extending through both bars and the rails, and other bolts extending through only the clamping bar and the rails.
11. A rail joint including the rails, a splice bar, a clamping bar of greater length than the splice bar, and joint bolts, certain bolts extending through both bars and the rails, and other bolts extending through only the clamping bar and the rails.
12. A rail joint including the rails, an inner splice bar, an outer clamping bar of greater length than the splice bar, and a double bolting unit consisting of a pair of bolts, one of which extends through both bars and the rail, and the other of which extends through the projecting ends of the clamping bar and the rail.

In testimony whereof I hereunto affix my signature in the presence of two witnesses.
